US00D726564S

(12) **United States Design Patent**
Endo et al.

(10) **Patent No.:** US D726,564 S
(45) **Date of Patent:** ** Apr. 14, 2015

(54) **DISPLAY MONITOR FOR VEHICLE**

(71) Applicant: **Alpine Electronics, Inc.**, Tokyo (JP)

(72) Inventors: **Hideki Endo**, Tokyo (JP); **Munetaka Ito**, Tokyo (JP)

(73) Assignee: **Alpine Electronics, Inc.**, Tokyo (JP)

(**) Term: **14 Years**

(21) Appl. No.: **29/508,874**

(22) Filed: **Nov. 12, 2014**

(51) LOC (10) Cl. **10-04**

(52) U.S. Cl.

(57) **CLAIM**

The ornamental design of the display monitor for vehicle, as shown and described.

DESCRIPTION

FIG. 1 is a perspective view of a display monitor for vehicle showing the new design in a panel-open status;

FIG. 2 is a perspective view thereof shown in a panel-closed status;

FIG. 3 is a top view thereof in a panel-closed status;

FIG. 4 is a bottom view thereof;

FIG. 5 is a front view thereof in a panel-open status;

FIG. 6 is a front view thereof in a panel-closed status;

FIG. 7 is a rear view thereof in a panel-closed status;

FIG. 8 is a left-side view thereof in a panel-closed status; and,

FIG. 9 is a right-side view thereof in a panel-closed status.

The broken lines are for environmental purposes only and do not form any part of the claimed design.
